DECATIZING CYLINDER

Armand L. Nazzaro, Montclair, N.J.

Application January 30, 1948, Serial No. 5,231

6 Claims. (Cl. 68—8)

1

My invention relates to decatizing and more particularly to decatizing cylinders of cloth treating machines or the like.

Heretofore, it has been the practice to employ machines wherein the decatizing cylinders are of a length corresponding approximately to the width of the cloth to be treated. Inasmuch as various widths of cloth are often treated in one establishment, it necessitates the establishment being equipped with a number of machines having cylinders of lengths corresponding approximately to the width of the cloth for the reason that it is not practical to treat a relatively narrow width of cloth by the employment of a relatively long cylinder and its correspondingly wide blanket because the margins of the blanket would extend beyond the edges of the cloth and thus absorb and become saturated by moisture produced by the condensation of steam. When the margins of the blanket are thus moisturized, the cloth being treated tends to absorb the moisture in a manner wherein the cloth becomes spotted or watermarked and thus damaged. Obviously, it is impractical to treat cloth of a width greater than the length of the cylinder and the width of the blanket. Inasmuch as the machines are quite expensive, it will be appreciated that quite an investment is necessary to provide a number of machines with different length cylinders in order to have available, in one establishment, means for treating cloth irrespective of the width thereof.

My invention overcomes the necessity of equipping an establishment with machines having cylinders of lengths for accommodating the various sizes of cloth, it being one of the objects of my invention to provide decatizing means which is so constructed and arranged that various sizes of cloth may be treated thereby without danger of the aforementioned damage.

Another object of my invention is to provide a decatizing cylinder having a plurality of cloth treating zones for accommodating cloth of various widths and which zones are capable of being rendered effective in a manner corresponding to the widths of cloth being treated.

A further object of my invention is to provide a method whereby cloth of various widths may be properly treated by decatizing means common to a plurality of widths.

An important object of my invention is to provide decatizing means including a cylinder having a plurality of cloth treating zones defined and rendered effective by compartments within the

2

cylinder together with means for rendering the compartments effective in a selected manner.

Another important object of my invention is to provide means of the foregoing described character which is simple in construction, durable in use, efficient in operation and economical in manufacture.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a diagrammatic view illustrating 20 textile treating apparatus having my invention incorporated therein.

Figure 2 is a longitudinal sectional view, partly in elevation, of the decatizing cylinder constructed in accordance with my invention.

Figure 3 is a sectional view taken on the line 25 3—3 of Figure 2.

Figure 4 is a sectional view taken on the line 4—4 of Figure 2.

Figure 5 is a sectional view taken on the line 30 5—5 of Figure 2.

Figure 6 is a detail sectional view taken on the line 6—6 of Figure 2.

In practicing my invention, as diagrammatically illustrated in Figure 1 of the drawings, I 35 provide a decatizing machine or apparatus having a decatizing cylinder 5, cloth loading and unloading rolls 6 and 7, guide and blanket straightener rollers 8 and 9, and a ternary of blanket supply rolls 10, 11 and 12, respectively. The rolls 40 6 and 7 are disposed on one side of the cylinder 5 while the rolls 10, 11 and 12 are disposed on the opposite side with the blanket straightener roller 9 being arranged subjacent the cylinder 5.

The decatizing cylinder 5 comprises a hollow 45 cylindriform body having a circumferential wall 14 provided with perforations 15 throughout its length and circumference and with sinistral and dextral end walls 16 and 17, respectively. The body is also provided interiorly with a pair of 50 spaced partitions or walls 18 and 19, the walls 16, 18, 19 and 17 defining sinistral end, intermediate and dextral end compartments 20, 21 and 22, respectively. The circumferential wall 14 is provided with a ternary of cloth treating zones 24, 25 and 26 defined by the compartments

20, 21 and 22, the widths of the zones 24, 25 and 26, in the present instance being approximately twelve, forty-two and twelve inches, respectively.

The end walls 16 and 17 are centrally mounted for rotation upon stationary bearings 27 and 28 with the latter having extending therethrough a pair of conduits 29 and 30, respectively. The inner ends of the conduits 29 and 30 communicate with the compartments 21 and 22, respectively, with the inner end of the conduit 29 extending through the wall 19 and having sealing engagement therewith by means of a packing joint J to permit rotation of the wall 19 relative to the conduit 29. The conduits 29 and 30 have extending therethrough siphon tubes 31 and 32 which have their inner ends right-angularly bent and terminating in proximity to the bottoms of the compartments 21 and 22, respectively. The bearing 27 is provided with a conduit 33 communicating with the compartment 20, the conduit 33 being provided with a siphon tube 34 having its inner end right-angularly bent and terminating in proximity to the bottom of the compartment 20 in the same manner as the tubes 31 and 32. The inner ends of the conduits 30 and 33 are provided with laterally extending branches or sections 35 while the innermost radial face of the wall 19 is formed with radially extending sleeves 36 communicating with the conduit 29 whereby steam is introduced into the compartments or suction established therein by negative pressure as hereinafter more fully described.

As illustrated in Figure 2 of the drawings, the outer ends of each of the conduits 29, 30 and 33 are provided with a T connection 37 having one end equipped with a cap provided with a packing gland 38 through which the respective siphon tube extends. Another end of each of the T connections 37 has secured thereto a three-way valve 39 connected to pipes 40, 41 and 42 leading to a steam supply, a negative pressure source and the atmosphere respectively. By selectively manipulating one of the valves 39, (1) steam may be introduced, from the steam supply, into the respective compartment through the conduit leading thereto for treating material wound about the zone defined by the compartment; (2) steam and moisture withdrawn from the compartment by the negative pressure source; or (3) the compartment opened to the atmosphere. Furthermore, when steam is not being introduced into the compartment, the latter may have liquid siphoned therefrom by a siphoning device connected to each of the siphoning tubes upon opening of the valve 43 controlling the respective tube.

The blanket supply rolls 10, 11 and 12 accommodate blankets of various widths, for instance, forty-two, fifty-four and sixty-six inches, respectively, for use in connection with treating textile material of approximately like widths when wound about the cylinder and disposed over one or more of the zones corresponding to the approximate width of the material to be treated. In other words, when it is desired to treat material having a width of approximately forty-two inches, the material, together with the blanket from the roll 10, is disposed about the cylinder over the zone 25. When the material to be treated has a width of approximately fifty-four inches, it is disposed, together with the blanket from the roll 11, about the zones 24 and 25 or 25 and 26. In instances where the material approximates sixty-six inches in width, it is disposed, together with the blanket from the roll 12,

about the zones 24, 25 and 26. Obviously, a length of relatively narrow material of approximately twelve inches may be treated by disposing the same, together with a suitable blanket, about the zone 24 or 26. When the material to be treated is thus disposed about the zone or zones, the compartments, defining the zones thus being utilized are supplied with steam.

From the foregoing, it will be apparent that my invention provides means whereby textile material of various widths may be treated by a single cylinder, the steam being supplied to the material through a selected compartment or compartments according to the width of the material to be treated. While in the present instance, I have disclosed my invention as being constructed in a manner to accommodate material of approximately three different widths, it is to be understood that the cylinder may be divided into a greater or lesser number of compartments than that disclosed and equipped with steam supplying and removing conduits and siphoning tubes for each of the compartments provided.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. A rotatable decatizing cylinder having its peripheral wall provided with a plurality of juxtaposed endless perforated zones of definite fixed widths effective for the steam treatment of textile material of approximately like and selectively combined like widths when the material is disposed about said wall, said cylinder being interiorly provided with spaced radial walls fixed to said peripheral wall and coacting therewith to define said zones and compartments arranged in lengthwise adjacency and with said compartments having definite lengths corresponding to the widths of said zones, respectively, steam supply means communicating with each compartment and with a steam source, and means selectively operable for rendering said steam supply means effective with respect to said zones, independently.

2. The structure as set forth and defined in claim 1 including, siphoning means communicating with each compartment and with a siphoning source.

3. The structure as set forth and defined in claim 1 including siphoning means communicating with each compartment and with a siphoning source, and means for controlling said siphoning means selectively.

4. A rotatable decatizing cylinder having a peripheral wall provided with a plurality of circumferentially extending and endless perforated juxtaposed zones of definite fixed widths effective for the steam treatment of textile material

of approximately like and selectively combined like widths when the material is disposed about said wall, said cylinder being interiorly provided with spaced radial walls fixed to said peripheral wall and coacting therewith to define said zones and compartments arranged in lengthwise adjacency and with said compartments having definite lengths corresponding to the widths to said zones respectively, a steam supply and a negative pressure conduit for communicating with said compartments and with steam and negative pressure sources respectively, valves in said conduits selectively operable for rendering said compartments effective for treating material applied to the zones defined thereby and for withdrawing moisture from said compartments, independently.

5. A rotatable decatizing cylinder having a peripheral wall provided with a plurality of circumferentially extending endless perforated zones arranged in side by side relation and being of definite widths effective for the steam treatment of textile material of approximately like and selectively combined like widths when the material is disposed about said wall, spaced partitions axially disposed within said cylinder and having their margins connected to the inner face of said wall, said partitions coacting with said wall to define said zones and compartments having fixed lengths corresponding to said widths of said zones respectively, steam supply means and siphoning means communicating with said compartments and with steam and siphoning sources, respectively, and including a steam conduit and

10
5

a siphoning conduit with one disposed within the other for communication with the same compartment, valve means selectively operable for rendering said steam supply means effective with respect to said zones independently, and control means for controlling said siphoning means selectively with respect to said compartments.

15
10
15
20

6. A rotatable decatizing cylinder having a peripheral wall provided with a plurality of circumferentially extending endless zones, said zones being spaced axially on said wall and being of definite fixed widths effective for the fluid treatment of textile material of approximately like and selectively combined like widths when the material is disposed about said wall, said cylinder being interiorly provided with fluid supply compartments of definite fixed lengths defining said zones, respectively, and for rendering the latter effective, and conduit means effective for supplying said compartments selectively and independently with fluid.
